DISPLAY RACK FOR CARTONS AND THE LIKE

Richard H. Dickson, Jr., Indianapolis, Ind., assignor to
The Coca-Cola Company, New York, N. Y., a corpora-
tion of Delaware

Application October 15, 1956, Serial No. 43,365

Term of patent 14 years

(Cl. D80—10)

The figure is a view in perspective of a display rack for cartons and the like embodying the instant design.

I claim:

The ornamental design for a display rack for cartons and the like, as shown.
